CLAIM

The ornamental design for a lap top computer carrying case, as shown and described.

DESCRIPTION

FIG. 1 is a perspective view of the interior of a lap top computer carrying case in accordance with the invention; FIG. 2 is a top plan view of the interior of a lap top computer carrying case in accordance with the invention; and, FIG. 3 is a cross-section view of the interior of the lap top computer carrying case, taken along line 3—3 of FIG. 2. The broken line showing of environment in FIGS. 1-3 is for illustrative purposes only and forms no part of the claimed design.
